UNITED STATES PATENT OFFICE

168,999

UNDERWATER KITE-TYPE CABLE
DEPRESSOR

John D. Isaacs, San Diego County, Calif., assignor
to The Regents of the University of California,
Berkeley, Calif., a corporation

Application August 10, 1951, Serial No. 16,229

Term of patent 14 years

(Cl. D71—1)

To all whom it may concern:

Be it known that I, John D. Isaacs, a citizen of the United States, residing in the county of San Diego, State of California, have invented a new, original, and ornamental Design for an Underwater Kite-Type Cable Depressor, of which the following is a specification, reference being had to the accompanying drawings, forming a part thereof.

Figure 1 is a top perspective view of an underwater kite-type cable depressor embodying my new design.

Figure 2 is a top view thereof.

Figure 3 is an end view as from the right-hand side of Figure 2.

Figures 4 through 9, respectively, are sectional views taken on the lines 4—4 through 9—9 of Figure 2.

Figure 10 is a cross-sectional view taken on the line 10—10 of Figure 2.

I claim:

The ornamental design for an underwater kite-type cable depressor, as shown.

JOHN D. ISAACS.
